EDWARD T. BURROWES, OF PORTLAND, MAINE.

BILLIARD OR POOL TABLE BED.

1,125,459.

Specification of Letters Patent.

Patented Jan. 19, 1915.

Application filed March 21, 1914. Serial No. 826,136.

To all whom it may concern:

Be it known that I, EDWARD T. BURROWES, a citizen of the United States, residing at Portland, in the county of Cumberland and State of Maine, have invented certain new and useful Improvements in Billiard or Pool Table Beds, of which the following is a specification.

This invention relates to improvements in beds for game boards, and more especially to beds for billiard and pool tables of the light, portable type intended for household use.

In carrying out my invention, I provide a foraminous metal base, preferably of steel, the perforations in the base being arranged so that the expansion and contraction of the metal, due to changes in temperature, will be taken up locally in the spaces formed by the perforations, thus allowing the base to be made of substantially the same dimensions as the interior of the frame without danger of exerting injurious pressure against the side bars or rails of the tables, and without danger of warping the base. The base is also provided with a bead near its edges which forms a more or less compressible connection between the bed and side bars, facilitating the fitting of the bed to the rails, and also compensating for any expansion of the base as a whole which is not taken up locally in the perforations. A rigid composite bed is formed by placing upon this base a molded top of plastic material, which is preferably interlocked with the base, this top, after hardening, having its upper surface ground off to make a smooth playing surface.

In order that the metal of the base may be free to expand and contract locally into and out of the perforations therein, and also in order that such expansion may not crowd the plastic material upwardly and thus affect the smoothness of the plastic top, the perforations in the base are kept clear of the plastic material, and preferably the material of the top is also formed with openings registering with the openings in the base. When the composite bed thus formed is fitted to a table frame, a layer or

sheet of suitable material, such as cloth or fiber-board, is interposed between the top and the billiard cloth and thus a smooth playing surface is provided over the perforated top. Beds thus made are light, portable and durable, and they may be sold and put into use as soon as the plastic material has hardened and the beds have otherwise been finished and assembled.

In the accompanying drawing, which illustrates the invention, Figure 1 is a top plan view of a billiard table bed embodying my improvements; Fig. 2 is a section through the same on the line 2—2 of Fig. 1; Fig. 3 is a section, on an enlarged scale, through a portion of the table on the line 3—3 of Fig. 1, showing the bed fitted to the table; and, Fig. 4 is a horizontal section through a modified form of table bed.

Referring to Figs. 1 to 3, inclusive, of the drawing, A indicates a billiard table bed as a whole, which is composed of a foraminous sheet metal base a and a top a' of plastic material. The base a may be of one continuous piece of metal, but in Figs. 1 and 2, it is shown composed of the sections 1, 2, and 3, suitably secured together by bolts or rivets 4 which extend through downwardly turned integral flanges 5 at the abutting edges of the sections. These flanges form transverse girder supports for the bed. The sides and ends of the bed are bent upwardly, as shown at 6, to form a bead and thence downwardly, as shown at 7, to form an attaching flange at the margins of the bed. The base is made of a size to fit snugly within the sides and ends 8 and 9 of the frame, and the arch or bead 6 forms a connection between the flange and the body of the base which may be bent slightly, if desired, to facilitate fitting the flanges to the frame. Also the bead 6 forms a connection which will yield to some extent if the base as a whole expands, and thus the thrust from such expansion will not cause injurious pressure against the side and end rails, or cause warping of the bed.

The base is closely perforated with narrow slots 10, which preferably extend

lengthwise of the base, and are arranged in staggered relation, as shown in Fig. 1, the main purpose of these perforations in the metal being to provide spaces into which the metal may expand so that the expansion will be taken up locally instead of being transmitted cumulatively to the margins of the base and thence against the rails, as would be the case with a continuous or unbroken base. Owing to the staggered relation of the slots, which preferably slightly over-lap, it will be seen that the pressure from expansion at any point toward the sides of the bed will be exerted in line with a plurality of perforations, and hence the metal will be crowded into the perforations and the expansion will be taken up locally instead of being transmitted to the edges of the bed. The metal base is covered by a layer of plastic material a' which is molded on to the upper surface of the base within the area surrounded by the marginal bead 6, but this top of plastic material does not fill the perforations in the base. It will be evident that if the hardened plastic material filled the perforations, this would interfere with the expansion of the metal into the openings, and also the expansion and contraction of the metal might tend to cause local fracture and upward bulging of the material on the surface of the top, which would interfere with the smoothness of the playing surface. For these reasons, the perforations 10 in the base are kept clear of the plastic material, and this may be done by placing pins temporarily in the openings 10 while the plastic material is being applied, or the plastic material may be cut out of the openings after the material has set.

In order to secure the plastic material of the top firmly to the base, the edges 10^a of the openings 10 are punched upwardly and turned slightly outwardly, as shown in Figs. 2 and 3, so that these edges will interlock with the plastic material. In making the composite bed, the metal base is first assembled, as shown in Fig. 2, and the plastic material is then applied, the perforations 10 being kept clear, and the plastic material is then ground off to provide a true upper surface.

In order that the perforations in the bed may not interfere with the smoothness of the playing surface, a thin layer of suitable material 13, such as a fiber or cloth, is laid over the surface of the plastic material before the billiard cloth 12 is applied. The bed is secured to the frame of the table by suitable means, such as wood screws 13, which pass through the flange 7.

In Fig. 4 I have shown a modification in which the metal base is made of one continuous piece, divided into sections, however, by transverse folds 14 in the metal,

which folds project downwardly and form transverse girders for the bed. Also in this view, the edges of the perforations 10^b are not turned upwardly so as to interlock with the cement or plastic material a^2 ; but here and there at a few points in the bed the plastic material is permitted to extend through the openings in the base to lock the plastic material of the top to the base. It is preferable, however, as illustrated in the previously described figures, to keep all of the perforations clear of plastic material, and for that reason the interlocking of the base and top by upward punching of the edges of the perforations is preferred. The base, however, may be made in a continuous piece, either with or without integral girder supports, suitable supporting means being provided, or it may be made in several connected sections as described. 85

What I claim is:

1. A composite billiard table bed comprising a foraminous sheet metal base and a top of plastic material molded thereon, but not filling the perforations in the base. 90

2. A composite billiard table bed comprising a foraminous sheet metal base and a top of plastic material molded thereon, the top having openings therethrough registering with the openings in the base. 95

3. A composite billiard table bed comprising a foraminous sheet metal base and a top of plastic material molded thereon, but not filling the perforations in the base, the edges of the openings in the base being turned upwardly and interlocked with the plastic material. 100

4. A composite billiard table bed comprising a sheet metal base having its playing area closely perforated with elongated slots or openings, and a top of plastic material molded thereon, but not filling said openings. 105

5. A composite billiard table bed comprising a sheet metal base having its playing area closely perforated with elongated slots or openings, and a top of plastic material molded thereon, but not filling said openings, the edges of the openings in the base being turned upwardly and interlocked with the plastic material. 110

6. A composite billiard table bed comprising a foraminous sheet metal base having integral transverse girders and a top of plastic material molded on the base but not filling the perforations therein. 115

7. A composite billiard table bed comprising a foraminous sheet metal base having its edges bent upwardly and thence downwardly to form a bead and an attaching flange, and a top of plastic material molded on the base. 125

8. A composite billiard table bed comprising a foraminous sheet metal base divided transversely into several sections, 130

the adjacent edges of the sections having downwardly turned flanges, said flanges forming girders, and the sides and ends of the base being bent upwardly and thence 5 downwardly to form a bead and an attaching flange, and a top of plastic material molded on the base.

In testimony whereof I have affixed by signature, in presence of two witnesses.

EDWARD T. BURROWES.
